THE COLUMBIA PLANOGRAPH CO., WASHINGTON, D. C.

UNITED STATES PATENT OFFICE.

FRANK E. BESSLER, OF AKRON, OHIO.

MOVABLE STAIRWAY.

1,188,395.

Specification of Letters Patent. Patented June 27, 1916.

Application filed January 27, 1915. Serial No. 4,710.

To all whom it may concern:

Be it known that I, FRANK E. BESSLER, a citizen of the United States, residing at Akron, in the county of Summit and State 5 of Ohio, have invented a new and useful Movable Stairway, of which the following is a specification.

The device forming the subject matter of this application is a structure of that general type in which a slidable stairway is supported upon a hingedly mounted panel, the construction under consideration being employed ordinarily for providing a stairway for a scuttle when it is desired that the 15 space below the scuttle shall be encumbered by the stairway only at the time that the stairway is in use.

One object of the present invention is to provide novel means for controlling the 20 drum whereby the panel is elevated and whereby the stairway is slid.

Another object of the invention is to provide a novel hand rail for a stairway and panel of the sort above mentioned.

With the above and other objects in view which will appear as the description proceeds, the invention resides in the combination and arrangement of parts and in the details of construction hereinafter described and claimed, it being understood 25 that changes in the precise embodiment of the invention herein disclosed can be made within the scope of what is claimed without departing from the spirit of the invention.

In the accompanying drawings:—Figure 1 shows in side elevation, a movable stairway constructed in accordance with the present invention, the panel being lifted to a closed position and the stairway proper being retracted. Fig. 2 is a top plan of the structure shown in Fig. 1; Fig. 3 is a side elevation showing the stairway and the panel in depending position; Fig. 4 is a cross section on the line 4—4 of Fig. 3; Fig. 5 is a cross section on the line 5—5 of Fig. 3; Fig. 6 is a cross section on the line 6—6 of Fig. 3; Fig. 7 is a side elevation of the actuating drum and attendant mechanism; Fig. 8 is a sectional detail, showing in elevation, and 30 at right angles to the showing of Fig. 7, sundry parts depicted in Fig. 7; Fig. 9 is a fragmental top plan showing the panel arms, parts being broken away; Fig. 10 is a

side elevation of the structure shown in Fig. 9; Fig. 11 is a section of the actuating drum. 55

In the accompanying drawings the numeral 1 indicates a portion of a ceiling provided with an opening 2. So far as the ceiling cooperates with the hinged panel and the slideable stairway hereinafter described, the ceiling may be considered as a “frame” and will be referred to herein-after by that term.

The invention includes a panel 3 mounted to swing vertically and connected with the frame 1 by means of a hinge 4. A flexible element 55 is secured to the panel 3 and depends from the same, to the end that the panel may be pulled downwardly, from the position shown in Fig. 1 to the position shown in Fig. 3. A stairway 14 is mounted to slide upon the panel 3 and comprises stiles 15. Duplicate mechanisms are provided for operatively connecting the slideable stairway 14 with the hingedly mounted panel 3, these mechanisms being located upon opposite sides of the stairway. But one of these mechanisms will be described in detail, and when, in the description, a point is arrived at where duplication no longer is present, notice will be given. 75

A support 5 is secured to the panel 3 adjacent the upper end thereof and a similar support 6 is secured to the panel adjacent the lower end of the panel. Referring now 80 to Fig. 5 it will be observed that straps 7 are secured to the inner faces of the supports 5 and 6, the straps 7 terminating in angularly disposed fingers 8, registering in grooves or guides 16 formed in the stiles 15. 90 By the structure above described, the stairway 14 is connected with the panel 3 to slide in the direction of the length of the panel. Through the oppositely disposed supports 5 and 6 and through the respective straps 7 95 pass rods 9 supporting tubular bearings 10 located between the supports (the support 5 being taken as typical) and the straps 7. Journaled upon the tubular bearing 10 is a wheel 11 which supports anti-frictionally 100 the lower edge of the stile 15 of the stairway 14. Thus, the movement of the stairway 14 longitudinally of the panel 3 is facilitated. Nuts 12 are mounted upon the ends of the rod 9 and the tubular bearing 105 10 serves to prevent the wheel 11 from being

pinched between the support 5 or 6 and the corresponding strap 7 (all of which will be readily understood from Fig. 5). Noting Fig. 4 and comparing the same with Figs. 3 and 1 it will be seen that an abutment 19 is secured to one of the stiles 15 adjacent the lower end of the stairway, the abutment 19 being provided with a finger 18 which is located in the groove 16. A similar abutment 19 is mounted upon the stile 15 adjacent the upper end of the stairway. When the panel 3 is swung upwardly as shown in Fig. 1 and when the stairway 14 is retracted, the abutment 19 coöperates with the support 6 to limit the sliding movement of the stairway in one direction. When the panel 3 is swung downwardly, as shown in Fig. 3, and when the stairway 14 is advanced and lowered, the abutment 17 coöperates with the upper support 5 to limit the downward sliding movement of the stairway. The abutment 17 is constructed like the abutment 19 shown in Fig. 4.

Passing now to Figs. 7 and 8 and comparing the same with Figs. 1 and 3 it will be noted that a bracket 20 is mounted on the frame 1, a yoke 21 being pivoted to the bracket 20, as shown at 22, to swing in a substantially vertical plane, which plane 30 is parallel to the plane defined by the panel 3, as the latter sweeps vertically upon its hinge 4. A shaft 23 is mounted in the yoke 21 and journaled for rotation upon the shaft 23 is a drum 62. A spiral spring 24 is secured at one end as indicated at 26 in Fig. 11 to the shaft 23, the other end of the spring 24 terminating in a hook 25, engaged through an opening in the tread of the drum 62. A ratchet wheel 33 is secured to the shaft 23 and coacts with a pawl 34 pivoted to the yoke 21. The shaft 23 is held against rotation by the pawl 34 and the ratchet wheel 33 under normal working conditions, but when it is desired to adjust the tension 45 of the spring 24, the pawl and ratchet mechanism above described permits this operation, a wrench or key (not shown) being applied to the shaft 23, one end of which is squared as indicated at 27 for this purpose.

50 It has been pointed out hereinbefore that the yoke 21 which carries the drum 62 is pivoted to the bracket 20, and a means is provided whereby when the panel 3 and the stairway 14 are moved, the yoke 21 and the drum 62 may be tilted, so as to permit a flexible element 51 to be led fairly upon the drum. To accomplish this purpose a link 29 is pivoted as indicated at 28 to the yoke 21, the link 29 being pivoted as indicated at 30 to a primary arm 31 which, in its turn, is pivoted as shown at 32 to the bracket 20. It is to be observed that the pivot element 30 is located eccentrically with respect to the pivot element 32. The primary arm 31 coöperates with a second-

ary arm 35 which is pivoted at 36 to a bracket 37 mounted on the panel 3. The secondary arm 35 is provided with a finger 38, coöperating with one edge of the primary arm 31 as will be understood best 70 from Fig. 3, to maintain the arms 31 and 35 in approximate alinement, when the panel 3 is swung downwardly and when the stairway 14 is lowered, as shown in Fig. 3. An adjustable pivotal connection is afforded between the primary arm 31 and the secondary arm 35, and reference may now be had properly to Figs. 9 and 10 for a clear understanding of the details of this feature of the invention. The primary arm 31 80 is provided adjacent its lower end with a longitudinally extended slot 39 and terminates at its lower end in an offset 46. In the secondary arm 35, adjacent its upper end, are formed a plurality of threaded holes 85 40. An angle member 41 is applied to the outer face of the primary arm 31 and in the angle member 41 are a plurality of smooth holes 42. Through any one of the holes 42 and through any one of the holes 90 40 passes a bolt 43, threaded into the holes 40 and provided with a nut 44 which is located adjacent the secondary arm 35. A screw 45 is journaled in the offset end 46 of the primary arm 31 and is threaded into 95 the projecting portion of the angle member 41. There is a lock nut 47 on the screw 45 which engages the element 46. It will be understood that the bolt 43 may be mounted in any of the openings 40—42 to effect an 100 increase in the effective length of the arms 35 and 31, and by loosening the lock nut 47 and rotating the screw 45, a further and finer adjustment may be made.

A sheave 48 is journaled in a frame 49 105 which is pivoted as indicated at 50 to the bracket 37. The flexible element 51 is secured at one end to the drum 62, as shown at 52 in Fig. 7, the flexible element passing around the sheave 48, and the lower end of the flexible element being secured to an eye 53 formed upon one end of a rod 64 (see Fig. 4) which connects the stiles 15.

The foregoing terminates the description 110 of the duplicated portions of the structure.

Located at one side of the stairway 14 and preferably at the right hand side thereof is a hand rail which is a composite structure. The hand rail is longitudinally extensible and comprises coöperating bars 56 120 and 57, the bars being connected for relative longitudinal movement by means of clips 58 (see Fig. 6) secured, each, to one of the bars 56 and 57 and registering slidably in grooves 59. The member 56 of the hand rail is supported by a pair of posts 60, rigidly attached to one of the stiles 15 of the stairway 14. The upper end of the hand rail 57 is secured to a post 61. This post 61 forms a part of the support 5 which is located at 130

the upper right hand corner of the panel 3. This detail will be understood readily, without specific illustration by presuming that the member 5, shown in Fig. 5, but reversed, owing to its location at the upper right hand corner of the panel, is elongated to form the post 61.

The operation of the structure above described is as follows: Presupposing that the parts are positioned as shown in Fig. 1, the flexible element 55 is grasped and the free end of the panel 3 is pulled downwardly, the panel swinging upon its hinged connection 4 with the frame 1. The panel 3 will then appear as shown in Fig. 3, the arms 31-35 moving from the folded position of Fig. 1 to the approximately alined position of Fig. 3. When the panel 3 is inclined as shown in Fig. 3, the stairway 14 is slid downwardly manually, or if the stairway is sufficiently heavy, the same will slide downwardly under its inertia, the latter operation ordinarily being the one which takes place.

Downward sliding movement of the panel is limited by the engagement between the abutment 17 and the support 5, the stiles 15 of the stairway 14 sliding along the wheels 11. As the stairway 14 moves from the position shown in Fig. 1 to that shown in Fig. 3, the flexible element 51 will be drawn out, the same moving over the sheave 48. By this operation, the drum 62 will be rotated upon the shaft 23 which is held fixed by the ratchet wheel 33 and the pawl 34. The spring 24 will thus be put under tension.

It is to be noted that as the arms 35-31 move from the position shown in Fig. 1 to the position shown in Fig. 3, the link 29 will be actuated, owing to the eccentric relation existing between the pivot elements 32 and 30. In this manner, the yoke 21 will be swung upon its pivotal mounting 22 and the drum 62 will be tilted, so that the flexible element 51 may be led fairly therefrom.

In order to restore the parts as shown in Fig. 3 to the positions shown in Fig. 1, the panel 3 is swung upwardly upon its hinged mounting 4 and the stairway 14 is slid upwardly on the panel, both of these operations being facilitated by the action of the spring actuated drum 62 and the flexible element 51. During the operation last above described, the yoke 21 will be swung on its pivotal mounting 22 due to the action of the link 29 and parts connected therewith, the flexible element 51 being led onto the drum 62 without over-treading.

Referring to the hand rail structure, it is to be observed that the bar 56 of the hand rail is connected with the stairway 14, the bar 57 being connected with the panel 3, as hereinbefore described. Therefore, when the panel 3 and the stairway 14 are moved from the positions shown in Fig. 3 to the positions shown in Fig. 1, the constituent

members 56 and 57 of the hand rail will telescope upon each other.

Having thus described the invention, what is claimed is:

1. In a device of the class described, a hingedly mounted stairway panel; a yoke; means for supporting the yoke for swinging movement; a yieldably actuated drum supported by the yoke; a flexible element connected with the drum and operatively connected with the panel; and mechanism operatively connecting the panel with the yoke to swing the yoke when the panel is moved.

2. In a device of the class described, a hingedly mounted panel; a stairway mounted to slide thereon; a yoke; means for supporting the yoke for swinging movement; a yieldably actuated drum supported by the yoke; a flexible element connected with the drum and with the stairway; and mechanism operatively connected with the panel and with the yoke to swing the yoke when the panel is moved.

3. In a device of the class described, a hingedly mounted panel; a stairway mounted to slide thereon; a yoke; means for supporting the yoke for swinging movement; a yieldably actuated drum supported by the yoke; a flexible element connected with the drum and with the stairway; means upon the panel for slidably engaging the intermediate portion of the flexible element; and mechanism operatively connecting the panel with the yoke to swing the yoke when the panel is moved.

4. A device of the class described comprising as constituent parts, a hingedly mounted panel and stairway mounted to slide thereon; a yoke; means for supporting the yoke for swinging movement; a yieldably actuated drum supported by the yoke; a flexible member connected with the drum and operatively connected to one of said constituent parts; and mechanism operatively connecting the yoke with one of said constituent parts to swing the yoke when said constituent part is moved.

5. In a device of the class described, a hingedly mounted panel; a stairway mounted to slide thereon; a longitudinally extensible hand rail comprising parts connected for relative longitudinal movement; means for connecting one of said parts to the panel; and means for connecting the other of said parts to the stairway.

6. In a device of the class described, a frame; a stairway panel hinged to the frame; primary and secondary arms forming a connection between the panel and the frame, the primary arm being provided with an elongated opening and the secondary arm being provided with an aperture; a supplemental member applied to the primary arm and provided with an aperture; a pivoted element located in the apertures and

in the opening; and an adjusting means connecting the primary arm with the supplemental member.

7. In a device of the class described, a frame; a stairway panel hinged to the frame; primary and secondary arms forming a connection between the panel and the frame, the primary arm being provided with an elongated opening and the secondary arm being provided with a plurality of apertures; a supplemental member applied to the primary arm and provided with a plurality of apertures registering with the apertures of the secondary arm; a pivot element extended through the opening and engaged with one pair of the aligned apertures; and a screw connecting the supplemental member with the primary arm.

8. In a device of the class described, a hinged mounted stairway panel; a yoke; means for supporting the yoke for swinging movement; a yieldably actuated drum carried by the yoke; a flexible element connected with the drum and operatively connected with the panel; a pair of pivotally connected arms, one of which is connected with the panel; means for upholding the other of said arms; and a link pivoted eccentrically to the last specified arm and connected with the yoke.

9. In a device of the class described, a

frame; a panel hinged to the frame; a stairway mounted to slide upon the panel; foldable arms pivotally connected with the frame and with the panel; a yoke mounted to swing upon the frame; a yieldably actuated drum journaled on the yoke; a flexible element connected with the drum and operatively connected with the stairway; and a link connected with the yoke, the link being eccentrically connected with the frame carried arm.

10. In a device of the class described, a frame; coöperating elements comprising a panel hinged to the frame and a stairway mounted to slide on the panel; foldable arms forming a connection between the panel and the frame; a yoke mounted to swing on the frame; a yieldably actuated drum carried by the yoke; means for connecting the yoke with one of the arms to tilt the yoke upon relative movement between the arms; and a flexible element connected with the drum and with one of said coöperating elements.

In testimony that I claim the foregoing as my own, I have hereto affixed my signature in the presence of two witnesses.

FRANK E. BESSLER.
